UNITED STATES PATENT OFFICE.

JACOB H. SCHAEFFER, OF BROOKLYN, NEW YORK.

DESIGN FOR A RING.

Application filed April 17, 1929. Serial No. 30,921. Term of patent 7 years.

To all whom it may concern:

Be it known that I, JACOB H. SCHAEFFER, a citizen of the United States, residing at Brooklyn, in the county of Kings and State of New York, have invented a new, original, and ornamental Design for Rings, of which the following is a specification, reference being had to the accompanying drawing, forming part thereof.

The figure is a perspective view of a ring, showing my new design.

I claim:

The ornamental design for a ring, as shown.

Signed at 234 W. 39th St., New York, in the county of New York, and State of New York, this 12th day of April 1929.

JACOB H. SCHAEFFER.
